REFRIGERATOR CAR FLOOR

John S. Lundvall, Chicago, Ill., assignor to Union
Asbestos & Rubber Company, Chicago, Ill., a
corporation of Illinois

Application May 6, 1939, Serial No. 272,071

3 Claims. (Cl. 105—422)

The present invention relates to metal floors and more particularly to metal floors for refrigerator cars, the invention being particularly well adapted for use in refrigerator cars equipped with overhead refrigerant containers.

It has become a common practice, with certain types of perishable commodities, to place the ice directly on top of the lading, with the result that the meltage from the ice descends upon the floor of the car.

Inasmuch as the conventional car floor is made of wood, with insulation underneath, the meltage which reaches the wood floor seeps through same and enters the insulation, causing it to become soggy, deteriorate and become generally worthless as an insulating medium. This requires expensive replacement of the insulation and necessitates the tearing up of the wood floor and replacement of any of the wood framework which has rotted due to the absorption of moisture.

An object of the invention is the provision of an improved water-tight floor for a refrigerator car which eliminates the necessity for the usual heavy floor boards, water-proofed fabric and the labor involved in applying the elements of the prior constructions.

More particularly, the present invention contemplates a construction adapted to contribute to the cooling efficiency of the car by providing a generally flat metal floor. It is well known that the salt brine resulting from meltage of the refrigerant has heat absorbing qualities due to its low temperature and it is my object to utilize this brine by permitting it to remain upon the metal flooring until it may be directed into the drainage gutter by natural forces or by the occasional tilting of the car in transit.

Another object is to provide a water-proof floor which extends upwardly of side walls of car to prevent the water on the floor from rising to a point where it might pass the sides of the floor and contact the insulation.

Another object is to provide a sectional metal floor having upstanding margins adjacent car walls but not secured thereto, whereby a section may be removed readily without removing fasteners through the floor sections and car walls.

Another object is to provide a metal floor which may be secured in the car without fasteners extending through the floor, eliminating a common cause of leakage into the insulation.

Another object is the provision of a metal floor having side troughs formed integrally therewith, eliminating seams and joints between trough and floor sheet, which are expensive to make and difficult to keep water-tight.

Another object is to provide a sectional metal floor adapted to be joined into a floor unit and having adjoining portions adapted to accommo-

date expansion and contraction of the metal without loosening the joints between sections.

Another object is to provide a sectional metal floor having means whereby a section may be removed for repair or replacement without removing the other sections.

Another object is to provide a metal floor having mounting means thereon for mounting the floor rack hinges, eliminating the necessity for using hinge securing bolts through the side walls and the possibility of leakage through the bolt holes, into the insulation.

Referring to the drawings:

Fig. 1 is a top plan view of the floor of a refrigerator car, with the wall of the car shown in section, and constructed according to the invention;

Fig. 2 is a vertical sectional view, taken on line 2—2 of Fig. 1.

Fig. 3 is a schematic plan view of the floor, showing the preferred mode of dividing the floor up into sections.

Fig. 4 is a transverse sectional view, taken on line 4—4 of Fig. 1.

Fig. 5 is a fragmentary sectional view, showing the supporting means for central floor stringer.

Fig. 6 is a fragmentary sectional view, taken on line 6—6 of Fig. 1.

Fig. 7 is a fragmentary sectional view, taken through one of the joints and joint strips, to illustrate fastening means to secure sections together.

Fig. 8 is a fragmentary sectional view, taken on line 8—8 of Fig. 7.

Fig. 9 is a fragmentary, transverse sectional view through one of the door posts.

Fig. 10 is a fragmentary, vertical sectional view taken on line 10—10 of Fig. 9.

Fig. 11 is a fragmentary, sectional view taken on line 11—11 of Fig. 12.

Fig. 12 is a fragmentary, sectional view taken on line 12—12 of Fig. 11.

In the drawings the usual parts of the car are shown, such as center sill 15; side sill 17; side sheet 19; side insulation 21; wood side sill 23; longitudinal floor stringer 25; floor rack stringers 27 and floor rack 29.

The side wall construction shown in the accompanying drawings is adapted for use with overhead refrigerant containers, having vertical side wall ducts for conducting the chilled air from the refrigerant compartment, adjacent the ceiling of car, to the space defined by the metal floor and the floor rack.

In the form of the invention shown in the drawings the floor comprises a metallic sheet 31, a wood sub-floor 33, a lower metallic sheet 35 and insulation 37 intermediate sub-floor 33 and lower metallic sheet 35. The sub-floor 33

may comprise a layer of boards extending laterally of the car with their ends supported by side sills 23 and their mid-portions supported by stringer 25. The plane portion of metallic sheet 31 may be supported in spaced relation to sub-floor 33 by means of spaced apart wood stringers 39, which may be nailed directly to sub-floor 33, and the spaces between these stringers may be filled with insulation 41.

Lower metallic sheet 35 may be secured, adjacent its longitudinal margins, to sills 15 and 17, as by welding, whereby to substantially close the space between sills 15 and 17. The floor insulation 37 may be placed upon metallic sheet 35, preferably in layers, intermediate opposite side sills 23 and may be held down against top surface of center sill 15, along longitudinal center of car, by floor stringer 25. Sub-floor 33 may be nailed directly to side sills 23 and stringer 25 and, when thus applied, will hold insulation 37 against displacement.

Means for securing the metal floor sections 31 against lateral and longitudinal movement in the car may comprise a pair of opposed angle bars 40, extending longitudinally of the car, adjacent the side walls thereof. Angle bars 40 may be secured to car framing in any suitable manner and may be provided with fastening means 42 adapted to cooperatively engage a portion of metal floor section 31. Fastening means 42 may comprise a bolt having its head welded to underside of horizontal leg of angle bar 40, the threaded portion of bolt projecting upwardly through said horizontal leg, adapted to register with an apertured portion of floor section 31 and to have a 35 tapped nut applied thereto.

The side wall of the car may comprise an outer metallic sheet 19 and a parallel, inner metallic sheet 43 spaced therefrom, with insulation 21 disposed between sheets 19 and 43. A wood lining 45 may be provided in inwardly, parallel, spaced relation to sheet 43, providing a side wall duct 47, the lower margin of which may terminate above the metal floor 31 and preferably on a plane with floor rack 29, to provide air communicating means between duct 47 and the space defined by floor rack 29 and metal floor 31.

The flooring of the car may comprise a plurality of substantially rectangular sheet metal sections 31, extending transversely of the car in abutting relationship with each other and cooperatively secured to each other, adjacent their longitudinal margins, by means of a joint strip 49. Metal floor section 31 may be provided with a depressed, transversely extending trough portion 51, adjacent each end of section 31, said trough portion 51 being preferably formed as an integral, downwardly extending corrugation, with adjacent, parallel marginal edge being outwardly and upwardly inclined.

The longitudinal margins of floor sections 31 which abut adjacent sections 31 may be provided with a downwardly extending wall portion 53 and a substantially parallel, spaced apart, upwardly turned edge portion 55, connected thereto by means of a lateral wall portion 57, said upwardly turned edge portion 55 being adapted for back-to-back engagement with edge portion 55 of adjacent floor section 31.

The abutting edge portions 55 may be provided with a plurality of registering perforations 59 and slotted portions 61, adapted to receive fastening means 63 and 65 respectively.

Joint strip 49 may comprise an elongated metal sheet or plate folded lengthwise to form an in-

verted U-shaped member and may be provided with transverse registering perforations through the spaced apart downwardly extending portions, adapted to receive fastening means 63 and 65. 5 The end portions of member 49 may terminate in downwardly extending, arcuate portions with outwardly and upwardly inclined extremities.

Means for anchoring section 31 to angle bars 40 may comprise angle brackets 66 which are 10 preferably secured to each end margin of section 31, one being applied adjacent each of the four corners. Bracket 66 may comprise an angle having a substantially vertical leg secured to end margin of section 31, as by welding, and a horizontal leg adapted to engage the top surface of the horizontal leg of angle bar 40, and may be provided with a perforation through the horizontal leg to receive the upstanding threaded portion of fastening means 42. The substantially vertical leg of bracket 66 may be formed to the contour of trough portion 51 of section 31, to which it is welded.

Means for securing the floor rack hinge 70 to floor section 31 may comprise a substantially horizontal plate 68, adapted to bridge the trough 51, which may be secured to section 31 by welding the opposite margins of plate 68 to adjacent portions of section 31. Plate 68 may be provided with one or more perforations to receive the bolts or other fastening means used to secure the hinge 70 to plate 68.

Floor sections 31, adjacent the doorway of car, may be provided with horizontal end margins 72 adapted to abut the underside of threshold member 74 and may be welded thereto in order to provide a water-tight joint.

Floor sections 31, adjacent the ends of the car, may have a substantially vertical longitudinal flange portion 76 adapted to abut adjacent portion of end wall, and may be provided with outlets 78 which are shown in the drawings as tubes or pipes having their upper end portions welded to the lowest portion of the troughs 51, whereby the moisture in the car may be drained to the outside of car. The outlet pipes 78 may be provided with any of the conventional air sealing means, preferably on the outside of the car, to allow the water to drain off freely and to prevent air communicating between the outside and inside of car, through outlet pipe 78.

The car structure includes the conventional side posts 80, door posts 82 and corner posts 84, upon which is supported the walls and roof structure of the car. In the drawings the wall insulation 21 is shown in parallel, abutting relationship with the inner surface of side sheet 19 and may be secured in this position by means of vertical posts 86, intermediate side posts 80 and inwardly spaced from side sheet 19.

Vertical posts 86 may be provided with longitudinally extending wood nailing stringers 88 and secured thereto by means of bolts 90 extending laterally therethrough, adapted to support the wood lining 45 which may be nailed to stringers 88.

The inner metallic sheet 43 is adapted to form a waterproof inner retaining wall for insulation 21 and may be bayed inwardly adjacent side posts 80 and may be flanged inwardly adjacent nailing stringer 88, with its vertical margins in vertical alignment with the inner face of stringer 88. The lower margin of sheet 43 may be downwardly and inwardly inclined to provide adjacent overlapping relationship with the upwardly and outwardly inclined end margins of floor sections

31, whereby the moisture descending upon the inner surface of sheet 43 will be directed into trough 51.

As shown in Figs. 4 and 12, the sub-floor 33 may be cut out to accommodate the downwardly extending arcuate wall portion 57 of floor section 31.

In one embodiment of the invention the upturned edge portions 55, of floor section 31, might have a plurality of perforations 59 to register with a like number of perforations in the joint strip (without using slots 61) but the preferred embodiment is to provide slotted portions 61 and perforations 59, in edge portions 55, in the proportion of three slotted portions 61 to one perforation 59 adjacent the flat portion of floor section 31. This provides means whereby bolts 65 may be inserted through those perforations in the joint strip 49 which register with slots 61 in edge portions 55 (in the assembled position), before the joint strip 49 is applied to abutting edges 55. Where the perforations in the joint strip 49 register with the perforations 59 of edges 55, the shouldered sleeve member 63 may be inserted through the aligned perforations 59, in edges 55, and the perforations in the joint strip 49, and the joint strip may be clamping secured to abutting edges 55 by means of a bolt which may be screwed up tight in the sleeve member 63.

After the joint strip 49 is secured in place by the fastening members the adjacent grooves may be filled with a suitable, preferably non-hardening compound. The compound may extend flush with the top surface of floor sections 31, whereby to provide means for making the joint watertight and to prevent the bolts loosening, as best shown in Fig. 6.

It will be noted that clearance is provided between the end margins of floor sections 31 and adjacent portion of the side wall of car, eliminating the difficulties involved where the metal floor sections are intended to fit snugly against the side walls of the car, due to variations in the width of the car and also variations in the lengths of the fabricated metal sections. By providing this clearance adjacent the ends of the floor sections 31 the sections are more easily handled during installation and, if a certain range of variations are to be accommodated, the perforations in the horizontal leg of bracket 66 may be elongated in a direction transversely of the car.

The floor racks 29 are preferably foraminous, to allow the chilled air adjacent the metal floor to rise through the apertures in the floor rack and enter the lading supported upon the floor racks. Floor racks 29 are preferably hinged adjacent the side wall of car and are preferably supported upon stringers extending laterally of the car, in order to accommodate circulation of air transversely of the car, as is customary where overhead refrigeration is used.

It is essential, where metal car floors comprise a series of metal sheets assembled into a unitary metal floor, that they be prevented from separating at the seams or joints, due to expansion and contraction of the unitary floor caused by extremes in temperature, and the present invention is provided with a joint structure whereby the expansion and contraction of the assembled floor sections 31 will be accommodated by a slight "springing" of the members 53 and 57 of floor sections 31 and also by the yieldable sealing compound, without affecting the edge portions 55 and associated joint strip 49.

While a metallic sheet 43 is shown in the drawings as the inner retaining wall for the side insulation 21 and as one of the duct walls, this wall may comprise a wood lining similar to wood lining 45 and spaced outwardly therefrom. If a wood lining is substituted for metallic sheet 43 the surface of the lining facing the duct may be covered with a waterproof paint or asphaltum compound to prevent the moisture within the duct from contacting the side insulation 21, and a suitable metal flashing strip may be secured to said lining adjacent the end portions of floor sections 31, and flared inwardly to provide overlapping relationship with the end portions of sections 31, whereby the moisture descending through the duct will be directed into the trough portion 51.

The longitudinal floor stringer 25 is preferably spaced from its supporting means, which is shown in the drawings as center sill 15, to eliminate the possibility of stringer 25 oscillating vertically as the floor load directly above the stringer may be increased or decreased. Stringer 25 is preferably mounted in a cradle member 94 which may be secured to center sill 15 by means of a bolt 96, which may be held down on center sill by means of one nut and the stringer 25 may be held down on the cradle member 94 by a second nut. While I have shown and described what I now consider to be the preferred manner of carrying out my invention, the same is merely illustrative and I contemplate all changes and modifications that come within the scope of the claims appended hereto.

The invention is hereby claimed as follows:

1. In a floor, the combination of a metallic flooring provided with a depressed trough portion adjacent a margin thereof and terminating in an outwardly and upwardly extending margin, and a plate-like hinge mounting member cooperatively secured to said metallic flooring in overlying bridged relationship with said trough portion and secured to said metallic flooring adjacent opposite margins of said mounting member.

2. In a compartment having a side wall, a metallic flooring provided with a depressed trough portion adjacent a margin thereof and terminating in an outwardly and upwardly extending margin adjacent and parallel to said side wall, a longitudinally extending member adjacent said side wall and said outwardly and upwardly extending margin and having an abutting engagement with a portion of said side wall, a bracket member secured to said outwardly and upwardly extending margin adapted for cooperative abutting engagement with said longitudinally extending member, and fastening means cooperatively securing said bracket member and said longitudinally extending member, whereby said metallic flooring will be secured against lateral movement relative to said side wall.

3. In a refrigerator car floor, the combination of sectional abutting metallic floor sheets extending transversely of the car and having upwardly turned margins adjacent the side wall of car, a plate-like hinge mounting member having one of its margins secured to said upwardly turned margin and having its opposite margin secured to the adjacent portion of the floor sheet, said mounting member being spaced from the portions of said sheet intermediate its secured margins.

JOHN S. LUNDVALL.
